CLAIM

The ornamental design for a display screen or a portion thereof with a graphical user interface, as shown and described.

DESCRIPTION

FIG. 1 is a front view of a first embodiment of a display screen or a portion thereof with a graphical user interface; and,

FIG. 2 is a front view of a second embodiment of a display screen or a portion thereof with a graphical user interface. The broken lines shown in the figures illustrate the environment and form no part of the claimed design.
